CLOSURE FASTENER

Filed Nov. 6, 1929

Inventor

William Mevis ~

By Clarence A. O'Brien, Attorney

UNITED STATES PATENT OFFICE

WILLIAM MEVIS, OF TUSCOLA, ILLINOIS

CLOSURE FASTENER

Application filed November 6, 1929. Serial No. 405,158.

This invention relates broadly to closure fasteners, and has more particular reference to a fastening device especially adapted for use with fences for securing the gate of the fence in a closed position.

A still further object of the invention is to provide a gate fastener which may be quickly and easily secured upon the gate post of the fence and adapted for fastening or retaining engagement with the gate when the latter is swung to a closed position for retaining the gate in said closed position.

A still further object of the invention is to provide a gate fastener of the character above mentioned which is comparatively simple in construction consists of but comparatively few parts and which can quickly and handily be moved to a releasing position for freeing the gate in order that the latter may be opened.

Other objects and advantages of the invention will become apparent during a study of the following description, taken in connection with the accompanying drawing; wherein

Figure 1 is a fragmentary view of a gate post therefor and illustrating the application of my invention thereto,

Figure 2 is a vertical transverse sectional view taken substantially on line 2—2 of Figure 1,

Figure 3 is a fragmentary detail horizontal sectional view taken through the fastener.

With reference more in detail to the drawings, it will be seen that I have designated the gate generally by the reference character 5, and the post against which the free end of the gate is adapted to abut when swung to a closed position, by the reference character 6.

The gate 5 may be of any conventional structure, and for the sake of example I have herein shown fragmentarily the gate as being of a frame structure.

The present invention comprehends the provision of a substantially U-shaped bracket formed of a single blank or strip of metal bent intermediate its ends to provide a pair of spaced parallel coextensive legs 7 and 8 respectively, each of said legs at their free ends terminating or merging into relatively wide

plate like attaching portions 9 and 10 respectively.

The plate like attaching portion 9 of the leg 7 is disposed against the inner face of the post 6 and is secured to said post through the medium of a screw 11 passing therethrough and engaging with the post. In lieu of the screw 11 any other suitable attaching means may be employed.

The leg 8 has its plate like attaching end bent laterally and at right angles thereto for position against the front vertical face of the post 6, said plate like attaching portion being secured to said post through the medium of screws or other suitable fastening elements 12.

Thus it will be seen that the bracket so secured to the post extends substantially at right angles to the post. Adjacent their plate like ends a spacer block 13 is arranged between the legs 7 and 8 as shown to advantage in Figure 3.

Loosely fitting within the U-shaped bracket between the bight of the bracket and the spacer block 13 is a retaining member designated generally by the reference character 14. The retaining element 14 is in the nature of a wire or metallic loop flattened as at 15 and having its lower end curved as at 16.

The retainer loop 14 is adapted for sliding movement between the legs 7 and 8 of the bracket and spaced bolts 17 extend transversely through the bracket, that is, through the legs 7 and 8, said bolts 17 passing through the loop 14, whereby the loop is normally supported in a depending position within said bracket as shown to advantage in Figure 2.

One of the horizontal rails or frame members 18 of the gate 5 at the free end of the gate has an angle plate 19 mounted thereon, the flange 20 of which rests on the upper edge of the rail 18 and has its forward edge projecting beyond the adjacent face of the rail 18.

In actual practice the U-shaped bracket will be mounted on the post 6 slightly above the gate rail 18 so that obviously as the gate is swung to a closed position the flange 20 of the plate 19 carried by the rail 18 will strike

against the lower curved end of the retaining loop 14 forcing the same vertically and upwardly between the legs 7 and 8, the gate continuing to a full closed position so that the 5 rail 18 of the gate will pass inwardly a sufficient distance toward the post 6 as to enable the loop 15 to drop down in front of the gate or to that position shown in Figure 2.

Adjacent its curved lower end the loop 14 10 is provided with a notch 21, with which notch 21 the free edge of the flange 20 of the plate 19 will engage thus retaining the loop 14 in pending position for retaining the gate 5 in a fully closed position.

15 In order to protect the fastener against the elements, there is provided a protector hood 22, which hood 22 may be of any suitable construction preferably formed of metal or other weatherproof material and this hood may be 20 opened at the inner end thereof, being substantially U-shaped in cross section, said hood 22 being of a length substantially equal to the length of the legs 7 and 8 proper.

The side wall of the hood 22 straddles the 25 legs of the U-shaped bracket with the closed end of the hood being preferably farthest remote from the post 6, and the bolts 17 fastened to the legs 7 and 8 also passed through the lower portion of the side walls of the hood 22 for securing the same in position on the bracket.

There is also employed a bolt which passes 35 through lower portions of the side walls of the hood 22, through the legs 7 and 8 and spacer block 13.

Thus it will be seen that the hood may be readily and easily placed in position for removing from the bracket, and that when in use will protect and shield the legs of the 40 bracket and the loop 14 against snow, rain, ice, and thus prevent the loop retainer 14 from becoming fast between the legs 7 and 8 by freezing as might be occasioned in cold weather.

45 In mild weather, the hood 22 may be removed. When the fastener is maintained in closed position by the loop 14, to release the gate for swinging the same to an open or partially open position, the returning loop 50 14 may be pushed upwardly to disengage the flange 20 from the notch 21, and as the gate is swung to an open position the curved end 16 of the retaining loop 14 riding over flange 20 of the plate 19 will of course cause the loop 55 14 to raise upwardly, and as the flange 20 clears the loop, the latter will fall vertically to return to its normal position.

It is believed that from the foregoing description, taken in connection with the accompanying drawings, a clear understanding of the operation and construction, utility and advantages of this invention will be had by those skilled in this art without a more detailed description.

65 Even though I have herein shown and de-

scribed the preferred embodiment of my invention, it is to be understood that the same is susceptible to changes fully comprehended by the spirit of the invention herein described and the scope of the appended claims.

Having thus described my invention, what I claim as new is:

1. In a gate fastener of the class described, a substantially U-shaped bracket comprising a pair of spaced parallel legs, said legs adapted to be secured to the fence post, one of said legs at one end adapted to be secured to one face of the fence post, and the other of said legs adjacent one end bent at right angles for attachment to the fence post at right angles to the first mentioned leg, bolts passing through said legs adjacent the connected ends of said legs, a retaining loop supported by said bolts for vertical movement between the legs of said bracket, said loop having a curved lower end normally projected downwardly from said bracket, said retaining loop being disposed in the bracket in spaced relation to said post whereby the gate may be swung to a closed position with its free end disposed between the post and the said loop, said loop provided with a notch, and a plate on said gate and extending laterally therefrom for reception into said notch when said gate is in a closed position.

2. In a gate fastener of the class described, a substantially U-shaped bracket comprising a pair of spaced parallel legs, said legs adapted to be secured to the fence post, one of said legs at one end adapted to be secured to one face of the fence post, and the other of said legs at one end being bent at right angles for attachment to the fence post at right angles to the first mentioned leg, bolts passing through said legs adjacent the connected ends of said legs, a retaining loop supported by said bolts for vertical movement between the legs of said bracket, said loop having a curved lower end normally projected downwardly from said bracket, said retaining loop being disposed in the bracket in spaced relation to said post whereby the gate may be swung to a closed position with its free end disposed between the post and the adjacent vertical end of said loop, said loop on said vertical end being provided with a notch, and a plate on said gate and extending laterally therefrom for reception into said notch when said gate is in a closed position, a hood mounted on said bracket for disposition over said retaining loop, and means for detachably securing said hood at its lower edge to the legs of said bracket.

3. In a gate fastener of the class described, a substantially U-shaped bracket comprising a pair of spaced parallel legs, said legs at one end adapted to be secured to a fence post, bolts passing through said legs to extend transversely of said bracket, a retaining loop supported on said bolts for vertical move-

ment between the legs of the bracket, said loop being supported by said bolts in said bracket in spaced relation to the fence post, whereby the gate may be swung to a closed position with its free end disposed between the fence post and an adjacent side of said loop, said side of said loop being provided with a notch, a plate on said gate having one edge portion extending laterally of the gate for reception into said notch when said gate is in a closed position, and a hood for said loop supported on said bracket.

In testimony whereof I affix my signature.
WILLIAM MEVIS.
